UNITED STATES PATENT OFFICE

148,457

DESIGN FOR A CONTAINER FOR PENS AND PENCILS

Victor Civita, New York, N. Y.

Application May 16, 1946, Serial No. 129,735

Term of patent 3½ years

(Cl. D58—12)

To all whom it may concern:

Be it known that I, Victor Civita, a citizen of the United States of America, residing at 550 Fifth Avenue, New York 19, in the county and State of New York, have invented a new, original, and ornamental Design for a Container for Pens and Pencils, of which the following is a specification, reference being made to the accompanying drawing, forming a part thereof.

Referring now to the drawings, Fig. 1 is a top plan view of a container for pens and pencils embodying my new design; Fig. 2 is a side view; Fig. 3 is a bottom plan view; and Fig. 4 is an end elevational view of the same.

I claim:

The ornamental design for a container for pens and pencils, substantially as shown.

VICTOR CIVITA.
